UNITED STATES PATENT OFFICE

ANDREW J. GORLICK, OF CLEVELAND, OHIO

LIQUID DISPENSER

Application filed September 25, 1929. Serial No. 395,067.

My invention relates to liquid dispensers and especially those used for filling measures.

One object of my invention is to provide a simple means for registering the amount of liquid as it passes thru the dispenser.

Another object is shown in the method of operating the intake and the release valves.

Other objects will be noted from the following description together with the accompanying drawings.

Referring to the drawings:

Fig. 1 shows a side elevation of the pump type dispenser with the lower release valve open and the measure being filled.

Fig. 2 shows a side elevation of the gravity type dispenser with the lever release valve closed and the container filled.

Fig. 3 is an enlarged front view of the dispenser with the lower release valve closed and the upper release valve compressed to allow the container to fill from the tank.

Fig. 4 is a side elevation of Fig. 3.

Fig. 5 is a broken away section showing the lower release valve in the open position.

Fig. 6 is a perspective view of the lower release valve.

Fig. 7 is a perspective view of the valve releasing lever.

Fig. 8 is a top view of the locking cap for the oil tank.

Fig. 9 is a bottom view of the locking cap.

Fig. 10 is a side elevation of the locking cap.

Again referring to the drawings, the pump tank is shown at 1 and the gravity tank at 1A each being equipped with a locking cap 2 which has a protruding portion 3 which slides under the edge of the opening 4 holding the cap 2 firmly in position when the key is turned in the lock 5.

Gravity tank 1A is also provided with an air vent 6 to allow the oil to flow freely into the glass container 7, this air vent is held in position with lock nuts 8 where it connects to tank 1A and top cover 26 of the container.

The oil flows into the container through pipe

9 either by way of the gravity tank 1A or by the use of the pump 10 from pump tank 1, and it is admitted by pushing up on rod 11, which supports lever arm 12, until adjusting screw 13 strikes and opens upper inlet valve 14, which permits the flow of liquid into the glass container 7.

The rod 11 is then drawn down until spring arm 15 trips register arm 16 and after register arm 16 is tripped arm 12 engages the arm 17 of valve 18 which automatically opens, releasing the oil from the glass container 7, the register 19 automatically registering the amount of oil that flows through into pipe 20 to valve 21 and is released to the measure 22 by drawing the valve lever 23 forward thus opening valve 21.

Spring arm 15 is fastened to lever arm 12 by suitable means at its upper end, allowing the spring arm 15 to retain its flexibility.

The registering device 19 is fastened to an upright post 24 which is an integral part of the base 25.

The glass container 7 is suspended between base 25 and top cover 26 which are connected by rods 27 through bosses 28 in top cover 26 and bosses 29 in base 25 and secured by nuts 30.

It will be seen that every time the container 7 is filled and emptied the register 19 will be operated to indicate the amount of liquid dispensed, and will thus provide a check on the sales.

I claim:

1. In a liquid dispenser, the combination of a container having an outlet valve, an inlet pipe depending into the container and provided with an inlet valve at its lower end, and a valve-operating device working in the container and movable to open either the inlet valve or the outlet valve, the outlet valve being located in the bottom of the container, and the inlet valve being located above the outlet valve, and said device comprising a push rod working through the bottom of the container and having an arm projecting be-

tween said valves and arranged to strike and open the inlet valve when moved upwardly and to strike and open the outlet valve when moved downwardly.

5 2. The combination stated in claim 1, and a register having an operating arm, and said device having a spring arranged to trip the arm of the register.

10 In testimony whereof, I do affix my signature.

ANDREW J. GORLICK.
